(57) **CLAIM**

The ornamental design for a toothbrush case, as shown and described.

DESCRIPTION

FIG. 1 is a perspective view of a toothbrush case showing my new design;

FIG. 2 is a front view thereof;

FIG. 3 is a rear view thereof;

FIG. 4 is a top view thereof;

FIG. 5 is a bottom view thereof;

FIG. 6 is a left view thereof; and,

FIG. 7 is a right view thereof.

The broken lines are for the purposes of illustrating portions of the toothbrush case and form no part of the claimed design.
